Everett Cook,
ATTORNEYS.

UNITED STATES PATENT OFFICE.

RICHARD G. KRAEUTER, OF IRVINGTON, NEW JERSEY.

MUCILAGE RECEPTACLE.

Application filed February 9, 1922. Serial No. 535,287.

To all whom it may concern:

Be it known that I, RICHARD G. KRAEUTER, a citizen of the United States, and a resident of Irvington, in the county of Essex and 5 State of New Jersey, have invented new and useful Improvements in Mucilage Receptacles, of which the following is a specification.

This invention relates to a mucilage receptacle of the type comprising a bottle or jar 10 to receive mucilage and a brush or dauber for applying the mucilage to a surface.

The objects of the invention are to provide a mucilage receptacle of this character embodying novel features of construction whereby the receptacle and dauber are maintained in a clean and sanitary condition; to provide in such a device means for preventing the dauber from picking up an excess 20 amount of mucilage; to provide improved means for maintaining the dauber always moist with mucilage and yet not immersed in the body of the mucilage, so as to be instantly ready for use; to provide a wick or 25 absorbent member immersed in the mucilage in the receptacle and having its upper end at all times positioned above the level of the mucilage, and means for maintaining contact between the dauber and said end of the 30 wick when not in use; to thus mount the said wick or absorbent member on a light spring in the receptacle, and place the dauber in the cover of the receptacle, said spring tending to hold said upper end of the wick at a 35 distance from the mouth of the receptacle less than the distance which said dauber enters the receptacle when the cover is applied, and the weight of said cover being sufficient to overcome the resistance of said spring 40 when the dauber engages the said end of the wick as the cover is applied; and to obtain other results and advantages as may be brought out by the following description.

Referring to the accompanying drawings, 45 in which like numerals of reference indicate the same parts throughout the several views,

Figure 1 is a side elevation of a mucilage receptacle embodying my invention as it is assembled for packing and transporting, 50 portions being broken away and shown in section;

Figure 2 is a vertical longitudinal sectional view through the receptacle with the cover clamping means removed;

Figure 3 is a top plan view of the receptacle with the cover removed, and 55

Figure 4 is a bottom plan view of the cover.

In the embodiment of the invention shown on the drawings the reference character 1 designates a receptacle of any suitable material, such as glass, porcelain, etc., said receptacle having an open end adapted to be normally closed by a cover 2 which is provided with an annular projecting flange 3 60 adapted to rest upon the edge of the receptacle.

An absorbent wick member 4 is mounted in the receptacle 1, the upper end of said wick member being provided with an enlarged head 6 to which is secured one end of a helical spring 5, the other end of which is adapted to rest upon the bottom of the receptacle. The spring 5 is so arranged as to maintain the head 6 of the wick above the level of the mucilage in the receptacle 1, and with this construction it will be understood that the mucilage will be conveyed upwardly through the wick 4 by capillary attraction to the head 6. The cover 2 is provided with an absorbent pad or the like 7 which is adapted to serve as a dauber or brush for applying the mucilage to a surface, and it will be observed that by engagement of the pad 7 with the head 6 of the wick the mucilage will be transferred to the pad and may be then applied to a surface. The spring is so positioned as to maintain the upper end of the wick 4 at a distance below the top of the receptacle 1 less than the distance which the pad 7 projects into the receptacle when the cover 2 is in position thereon, and the weight of the cover 2 is preferably sufficient to overcome the resistance of the spring 5. Thus, 70 when the cover is applied to the receptacle 75 the wick 4 will be forced downwardly against the action of the spring 5, and the head 6 of the wick will be maintained in contact with the pad 7.

With this construction the receptacle can 100 be maintained in a clean and sanitary condition, and an excess amount of mucilage is prevented from being picked up by the pad 7. The constant contact of the wick and the pad when the cover is in position on the 105 receptacle also maintains the dauber in condition for instant use.

For the purpose of packing and trans-

porting mucilage in the receptacle, the outer end of the receptacle 1 may be threaded as at 8 and a flanged clamping ring 9 threaded upon the receptacle and overlapping the 5 flange 2 of the cover as clearly shown in Figure 1, a packing ring 10 being interposed between the cover and the receptacle. This clamping ring 9 may also be utilized when the receptacle is out of use for any 10 great length of time in order to seal the receptacle and maintain the mucilage in proper condition.

The invention has been shown in connection with a receptacle for mucilage, but it 15 will be understood that it is capable of use as a moistening device or for like purposes. While I have shown and described one possible embodiment of my invention, it will be understood that this only for the purpose 20 of illustrating the principles thereof, and that many modifications and changes can be made in the detail construction of the invention without departing from the spirit or scope thereof. Therefore, I do not desire 25 to be understood as limiting myself except as required by the following claims when construed in the light of the prior art.

Having thus described the invention, what I claim is:

- 30 1. The combination of a receptacle to receive a liquid and having an open end, an absorbent member adapted to be immersed in said liquid with a portion thereof above the level of said liquid, a member for applying said liquid to a surface and adapted to close said open end of the receptacle, and yielding means for maintaining contact between said absorbent member and said applying member when the latter is in closing 35 position on the receptacle.
- 40 2. The combination of a receptacle to re-

ceive a liquid and having an open end, an absorbent member adapted to be immersed in said liquid, a member for applying said liquid to a surface and adapted to close said 45 open end of the receptacle, and yielding means for maintaining a portion of said absorbent member above the level of said liquid so that as said applying member is placed in closing position it engages said absorbent member and forces the same 50 downwardly into the receptacle against the action of the said yielding means to maintain contact between said applying member and said absorbent member.

55 3. The combination of a receptacle to receive a liquid and having an open end, an absorbent member adapted to be immersed in said liquid, a spring for supporting said absorbent member in the receptacle with a 60 portion above the level of said liquid, a member for applying said liquid to a surface and adapted to close said receptacle, said member being of a weight sufficient to overcome the resistance of said spring and 65 adapted to engage said absorbent member as the applying member is placed in closing position on said receptacle and force said absorbent member downwardly into the receptacle against the action of said spring.

70 4. The combination of a receptacle to receive a liquid and having an open end, a removable cover for said open end having an absorbent surface on the under side thereof, an absorbent member adapted to be 75 immersed in said liquid, and yielding means for supporting said absorbent member in said receptacle with a portion thereof above the surface of said liquid and in engagement with said absorbent surface on said 80 cover.

RICHARD G. KRAEUTER.
